UNITED STATES PATENT OFFICE.

WALTON CLARK, OF PHILADELPHIA, PENNSYLVANIA, ASSIGNOR TO THE UNITED GAS IMPROVEMENT COMPANY, OF SAME PLACE.

APPARATUS FOR MANUFACTURING GAS.

SPECIFICATION forming part of Letters Patent No. 404,520, dated June 4, 1889.

Application filed October 26, 1888. Serial No. 289,199. (No model.)

To all whom it may concern:

Be it known that I, WALTON CLARK, of the city and county of Philadelphia, State of Pennsylvania, have invented a new and useful Improvement in Apparatus for Manufacturing Gas, of which the following is a true and exact description, reference being had to the accompanying drawings, which form a part of this specification.

10 My invention relates to the construction of apparatus intended to make a mixed gas—to wit, water-gas and ordinary coal-gas from bituminous coal—my object being to generally improve the construction and efficiency of 15 such apparatus, and more particularly to so combine and arrange the various parts making up my apparatus as to save for use or storage substantially all of the coal-gas.

Generally speaking, the leading characteristic of my invention consists in the herein-after-described construction and arrangement of the parts, whereby the externally-heated coal-distilling retorts are so arranged with respect to the water-gas generators and the hydraulic main or passage leading to the storage-tank that the coke can be pushed from them into the generators, while at the same time the coal-gas, either alone or mixed with the gas from the generators, traverses the 25 retorts and escapes from near their closed or charging ends into the main. The inclined arrangement of the retorts, the double arrangement of the system, and the system by which the Siemens gas is used to heat the 30 retorts, as hereinafter described, are also valuable and important elements of my new invention.

Reference is now had to the drawings, which illustrate a small gas-producing apparatus embodying my invention in what I believe to be its best form, and in which—

Figure 1 is a front elevation of the apparatus partially sectioned on the line L M of Fig. 8. Fig. 2 is a sectional elevation on the 45 line A B of Fig. 4; Fig. 3, a similar sectional elevation on the line C D of Fig. 4. Fig. 4 is a front sectional elevation, the part to the right on the line G H of Figs. 2 and 3 and the part to the left on the line E F of the same 50 figures. Fig. 5 is a front sectional elevation, the part to the right on the line K W of Fig.

3 and the part to the left on the line I J of the same figure. Fig. 6 is a sectional plan on the line X X of Figs. 2 and 3; Fig. 7, a sectional plan on the line Y Y of Figs. 2 and 3, 55 and Fig. 8 a sectional plan on the line O P of Fig. 2.

The apparatus as shown is a double one, this construction being essential, as will be seen, where a continuous mixture of water-gas and coal-gas is to be made with but little waste of the coal-gas or admixture with Siemens gas.

A A are generators of the kind commonly used in the alternate production of Siemens and water gas, A' being the air-blast pipe, a the coal-hole, and a' the ash-pit. I provide these generators with two openings near their tops, one, indicated by a², being for the escape of Siemens gas when it is being made, and the other a³ serving for the escape of the water-gas and also for the entrance of coke from the retorts, as will be hereinafter described.

B indicates the structure containing and supporting the retorts and flue-systems, to be 75 described. The mere construction of the structure B is of course unimportant and no part of my invention.

C is an inclined passage or conduit passing upward from the opening a³ and into the bottom of a chamber C'. The passage C is provided with a valve and valve-actuating rod, as indicated at c', so that it can be closed at will.

C' is a chamber having a hopper-shaped bottom, as is best seen in Fig. 2, and terminating in the conduit C.

D D D are coal-distilling retorts, preferably inclined, as shown, opening at one end (the lowest) into the chamber C', and having at 90 their other end (the highest) an opening d, from which extend pipes E E', leading into a hydraulic main E², the upper ends of the retorts having removable caps or covers d², through which bituminous coal can be from 95 time to time introduced into them, small blocks d³ being attached to handles d' extending to the outside of structure B, so that when thrust forward they will lie in the open mouth of the retorts and prevent the coal from sliding through them into chambers C'. When the coal is coked and the blocks drawn back 100

into chambers C', the coke can easily be forced out of the retorts into the chamber.

Returning again to the generators, A F F are pipes or conduits leading from the opening 5 a². As shown, they are virtually made up of a single pipe divided by a cross-partition f. f' f' are openings leading out of pipes F, and f² f² valves with their operating rods or handles arranged to cover and uncover the openings f'.

G is a chamber into which both openings f' lead, and in which the valves f² are situated; G', a conduit or passage leading from the box G to a flue or passage G², which opens at each 5 end into the two passages or flues G³, which extend beneath the two sets of retorts D.

g g, &c., are openings extending upward from the flue G³ into the chambers II, which in turn connect with chambers I by means of 5 o passages h'. The chambers I are formed by partitions h, which also separate the chambers II from each other, and, as will be seen, the retorts D are either wholly or partially embraced by the chambers I, which are arranged 5 side by side throughout their length. These chambers I open through a series of passages i i into passages or flues J, which in turn open through apertures k into the passages or flues K, which should extend beneath the lower 5 o retorts D D, as shown, and at their farther end communicate through passages k' with flues L L', said flues, of which there are two for each set of retorts, opening into the cross-passages L² L². From these cross-passages 5 L² apertures l lead into flue-passages M, and thence into cross-passages N, leading to a gas-outlet, as O in Fig. 5, which should communicate in some convenient way with a stack S.

P P are air-inlet passages or flues communicating with the bottom of a series of flues or passages Q, arranged alternately with the flues M, and opening through apertures r into cross-passages R, from which flues R', which should run alongside of the passages 5 L', lead.

R² R² are passages leading from the flues R' R', and lying, as in the case of the passages G³, beneath the retorts D. From these 5 o passages R² small passages r², arranged along their length, lead into chambers II.

The above-described plan for utilizing the Siemens gas in the external heating of the retorts while an important is not an essential feature of my invention, and, as is clearly indicated in the claims, I claim as new the described combination of the generators with the retorts and the gas-pipes leading from the retorts irrespective of the means used to heat the retorts.

T T are chambers adapted for use when it is desired to enrich the water-gas made in generators A by hydrocarbon oil. They communicate with the top of the generators by means of conduits U, leading into openings 5 a¹ in the generators, and are provided with checker-work of refractory material, as indicated at T', oil-injector V, and gas-exit pas-

sages T², through which, by any of the well-known systems in use, communication is made with the stack and either directly or indirectly with the gas-main leading to the storage-tank. 70

The operation of my apparatus is as follows: Fires are made in the generators A A, and the valves c' being closed the Siemens 75 gas escapes through passages F F and openings f', which, in the beginning, would both open into box G. Thence the gas passes through flue G' into the flue G², which is common to both sets of retorts, and from which the 80 gas escapes into both of the flue-passages G³ and through the series of passages g into the two sets of chambers II. While the gases are following this course and after the flues and retorts are properly heated, the air is 85 admitted at P P and passes upward through passages Q into the cross-passage R, and thence through passages or flues R', through the flues R², from which it escapes through small passages r² into the chambers II, where 90 it mingles with the Siemens gas from the generators, which is ignited by the mixture. The burning gases pass upward through passages h' into the chambers I, where they are brought into contact with the retorts D, and 95 from which they pass through openings i into flues J, thence into flues K, both of these sets of flues being in contact with the lower retorts D D, and thence through passages k' and L L' and into the cross-flues L², which 100 distribute them among the passages M, lying side by side with the air-passages Q. From these passages M the gases escape into the cross-flues N and thence to the stack. The arrangement of the air-passages in contact 105 with the passages through which the hot gases escape of course results in heating the air to a high degree before it mixes with the Siemens gas in the chambers II. The particular arrangement shown is not new with me, but is 110 one of many similar devices well known in the arts, and any of which could of course be used to accomplish the same purpose.

When the retorts D are sufficiently heated, or, indeed, before they are heated, if desired, 115 bituminous coal is introduced into them, the blocks d³ being pushed into their lower ends to prevent the coal from sliding through them into chambers C'. Whatever gas is driven off from the coal in the retorts escapes through 120 the pipes E E' into the hydraulic main E², and is conducted to the reservoir. The apparatus being at a proper temperature, the air-supply is cut off from one of the generators, the valve f² moved so as to close the passages 125 F, leading from this generator, and the valve c' moved so as to open the passage C, leading from it. Steam is then admitted at the bottom of the generator through pipe A², and the water-gas formed by the decomposition of the 130 steam in passing through the incandescent charge in the generator passes then through opening a³ and passage or conduit C into chambers C', and thence through the retorts

D D D, escaping, together with the gas distilled from the coal by the external and internal heat applied to the retorts through pipes E E' into main E². While this is going on, the second generator continues to make Siemens gas, which is delivered, in the way already described, into the common flue G², and thence distributed so as to heat both sets of retorts externally. When the coal has been converted into coke, it is pushed out of the retorts D into the chamber C', falling through which it enters the inclined passage C and falls into the generator. When this fresh charge of coke is delivered to the generator, the valve c', leading from it, should be closed, and the valve f², closing the passage F, which communicates with it, open, the steam-passage A² closed, and the air-blast A' open, while the other generator should be arranged to manufacture water-gas and deliver it to the other set of retorts.

It is of course evident that by a proper system of charging and discharging the various retorts with corresponding changes or alterations of the action of the generators, the whole apparatus may be maintained at the efficient temperature and the manufacture of gas carried on continuously and with great economy. In no event is any appreciable amount of the coal-gas wasted, nor need any Siemens gas be mixed with the water-gas and coal-gas, while at the same time whatever amount of such gas is necessarily produced is economically used in the external heating of the retorts.

While, as I have already stated, I prefer the double arrangement shown and described, my apparatus contains valuable novelties of construction apart from its double character, and I therefore do not limit myself to the double apparatus, except where this limitation is expressly made in the claims.

In my preferred apparatus it will not, I think, be necessary or desirable to carburet the gas by the use of hydrocarbon oils. If, however, it is desired to so carburet the gas, it will best be done by the use of the device indicated in the drawings. A chamber, T, filled with checker-work, as indicated at T', should be provided and connected with the generator by a conduit, such as U. Siemens gas from the generator should be passed through this chamber and preferably ignited in it, so as to heat the checker-work to a proper temperature, the gases escaping through passage T² and being conducted thence to the stack in the usual way, their surplus heat being utilized, if desired, to raise the temperature of any of the other parts of the apparatus. When the generation of Siemens gas is stopped and that of water-gas begun, any desired portion of such gas may be made to pass through the carburetter T, and oil is injected into the gas as it enters it through the oil-injector V, the oil vapor and gas being fixed and made into a permanent gas by the intense heat of the checker-work, and the gas

being then conducted in any usual way to the storage-tank and mixed with the gases coming from the retorts D. I have not shown a 70 pipe-connection uniting the chamber T with the main E'', as such a connection can be made in any number of ways or the connection can be made in the holder. These chambers T may, as aforesaid, be conveniently 75 used with my improved device; but I do not claim their use to constitute a new combination or to involve invention.

Having now described my invention, what I claim as new, and desire to secure by Letters 80 Patent, is—

1. In an apparatus for manufacturing gas, the combination of a generator provided with air-blast and steam pipes, a set of retorts arranged above the generator, a chamber into 85 which the retorts open freely at one end, a passage extending from said chamber downwardly into the generator, gas-pipes leading from the ends of the retorts opposite to those opening into the chamber aforesaid, combustion-chambers arranged externally around the retorts, said retorts being closed with respect to the combustion-chambers, a flue system leading from the generator into said combustion-chambers, an air-flue system also 90 leading into the combustion-chambers, and valves in the inclined passage and flue leading from the generator, whereby both can be opened or closed at will, all as and for the purpose specified. 100

2. In an apparatus for manufacturing gas, the combination of a generator provided with air-blast and steam pipes, a set of inclined retorts arranged above the generator, a chamber into which the retorts open freely at one end, a passage extending from said chamber downwardly into the generator, gas-pipes leading from the ends of the retorts opposite to those opening into the chamber aforesaid, combustion-chambers arranged externally 105 around the retorts, said retorts being closed with respect to the combustion-chamber, an independent flue system leading from the generator into said combustion-chambers, an air-flue system also leading into the combustion-chambers, and valves in the inclined 115 passage and flue leading from the generator, whereby both can be opened or closed at will, all as and for the purpose specified.

3. In an apparatus for manufacturing gas, 120 the combination of a generator provided with air-blast and steam-pipes, a set of retorts arranged above the generator, a chamber into which the retorts open freely at one end, a passage extending from said chamber downwardly into the generator, gas-pipes leading from the ends of the retorts opposite to those opening into the chamber aforesaid, combustion-chambers arranged externally around the retorts, said retorts being closed with respect to the combustion-chambers, an independent flue system leading from the generator into said combustion-chambers, an air-flue system also leading into the combustion- 130

chambers, a flue system leading from the combustion-chambers to the stack arranged to heat the air-flue system, and valves in the inclined passage and flue leading from the generator, whereby both can be opened or closed at will, all as and for the purpose specified.

4. In an apparatus for manufacturing gas, the combination of two independent generators provided with air-blast and steam pipes, two sets of retorts arranged above the generators, two chambers, one for each set of retorts, into which said retorts open freely at one end, a passage leading downward from each chamber to the top of one of the generators, so as to connect each independent chamber with one of the generators, gas-pipes leading from each retort at the end opposite to that opening into the chambers aforesaid, combustion-chambers arranged externally around each set of retorts, said retorts being closed with respect to the combustion-chambers, an independent flue system consisting of separate and independent flues leading from each generator to a common flue-connection with both sets of combustion-chambers, air-flues also leading into the combustion-chambers, valves arranged to close the passage leading from the generators to the chambers into which the retorts open, and valves arranged to close each of the passages leading from the generators to the common flue aforesaid.

5. In an apparatus for manufacturing gas, the combination of two independent generators provided with air-blast and steam pipes, two sets of inclined retorts arranged above the generators, two chambers, one for each set of retorts, into which said retorts open freely at their lower ends, a passage leading downward from each chamber to the top of one of the generators, so as to connect each independent chamber with one of the generators, gas-pipes leading from each retort at their upper ends, combustion-chambers arranged externally

around each set of retorts, said retorts being closed with respect to the combustion-chambers, a flue system consisting of independent flues leading from each generator to a common flue having connection with both sets of combustion-chambers, air-flues also leading into the combustion-chambers, valves arranged to close the passages leading from the generators to the chambers into which the retorts open, and valves arranged to close each of the passages leading from the generators to the common flue aforesaid.

6. In an apparatus for manufacturing gas, the combination of two independent generators provided with air-blast and steam pipes, two sets of inclined retorts arranged above the generators, two chambers, one for each set of retorts, into which said retorts open freely at their lower ends, a passage leading downward from each chamber to the top of one of the generators, so as to connect each independent chamber with one of the generators, gas-pipes leading from each retort at their upper ends, combustion-chambers arranged externally around each set of retorts, said retorts being closed with respect to the combustion-chambers, a flue system consisting of independent flues leading from each generator to a common flue having connection with both sets of combustion-chambers, air-flues also leading into the combustion-chambers, a flue system leading from the combustion-chambers arranged in close contact with the air-flue system, so as to heat the entering air, valves arranged to close the passages leading from the generators to the chambers into which the retorts open, and valves arranged to close each of the passages leading from the generators to the common flue aforesaid.
